UNITED STATES PATENT OFFICE.

HUGH L. GADDIS, OF MACOMB, ILLINOIS, ASSIGNOR TO AMERICAN STEEL PRODUCTS CO., OF MACOMB, ILLINOIS, A CORPORATION OF ILLINOIS.

BROODER STOVE.

Application filed May 10, 1924. Serial No. 712,229.

To all whom it may concern:

Be it known that I, HUGH L. GADDIS, citizen of the United States, residing at Macomb, in the county of McDonough and 5 State of Illinois, have invented certain new and useful Improvements in a Brooder Stove; and I do hereby declare the following to be a full, clear, and exact description of the invention, such as will enable others 10 skilled in the art to which it appertains to make and use the same.

My invention relates to draft control arrangements for stoves and more particularly to arrangements suitable for controlling the 15 draft of slow burning stoves. Generally speaking, it is the object of my invention to provide a simple, easily manufactured and inexpensive construction for this purpose and one which will readily lend itself for 20 accomplishing various highly desirable purposes as needed in connection with heating stoves in which the fuel is consumed at a relatively low rate. More particularly, my invention provides a stove construction for 25 this purpose in which the draft is checked by the admission of air to the flue from outside of the combustion chamber of the stove; provides means whereby the check draft air is warmed by the stove so as to produce a 30 speedily acting check draft current, and provides simple means for deriving at least a portion of this check draft current from the ash-pit of the stove. It also provides a construction which can readily be employed for 35 this purpose which can readily be employed with cheap grades of soft coal, which is easily adapted for use in connection with a stove or heater having a draft-retarding flue chamber under the flue pipe proper, and 40 which can readily be employed in connection with suitable means for catching drip from the flue. Still further and also more detailed objects will appear from the following specification and from the accompanying 45 drawings, in which

Fig. 1 is a central, vertical and longitudinal section through a stove embodying my invention in a form particularly adapted for use within the hover or hood of a 50 brooder.

Fig. 2 is a plan view of the same embodiment.

Fig. 3 is a transverse section through the upper portion of the same stove, taken along 55 the line 3—3 of Fig. 2.

Fig. 4 is a horizontal section through Fig. 1 along the line 4—4 of Fig. 1.

Fig. 5 is a rear view of the same brooder stove.

Fig. 6 is a rear view of an embodiment 60 allied to that of Figs. 1 to 4, but having an auxiliary check draft duct arranged for taking part of the check draft air directly from outside the stove.

Figs. 7 and 8 are enlarged horizontal sections, taken respectively along the line 7—7 of Fig. 5 and 8—8 of Fig. 6.

In one of its immediate commercial applications, the stove or heater of my invention is particularly adapted for use in connection 70 with cheap grades of soft coal in maintaining a slow fire at an even temperature, such as is needed for example under the hood or hover of a brooder. Coal burning stoves for this purpose have heretofore been regulated 75 by means of thermostatically controlled check dampers arranged for admitting air from outside the stove to some interior portion of the stove, such as the upper part of the combustion chamber, but this arrangement has the objection that the admitted air unduly chills the combustion chamber of the 80 stove and hence temporarily produces an excessive cooling of the stove so that the temperature within the brooder fluctuates 85 too much. On the other hand, if the check draft air is secured by opening a lateral connection between the flue or flue pipe and the outer air, the draft in the flue pipe is apt to be too slight, particularly with a slow burning 90 fire in the stove, to have any speedy effect. Consequently, the temperature regulation in this case is undesirably sluggish. Furthermore, many of the draft control arrangements as heretofore provided are 95 unduly cumbersome, complicated and expensive in construction, and frequently also involve an undesirably close fitting of certain stove parts.

With my present invention, I avoid all of 100 the objections above named. I accomplish this partly by admitting the check draft air to a draft chamber or flue chamber which effectively forms the lower portion of the flue and which is connected to the combustion chamber of the stove through passages of limited size, partly by taking at least a 105 part of this check draft air from the ash-pit of the stove, partly by employing a simple pivoted damper located where a relatively 110

short and simple connection can be made from it to the usually thermostatically actuated lever arm, and partly by arranging the check draft duct or ducts so that the air 5 entrapped in the same will be continuously warmed and ready to start a forcible upward current as soon as the damper is opened.

Referring to the embodiment of Figs. 1 10 to 5 inclusive, this shows a heater or stove having a rocking grate 1 disposed at the top of the ashpit 2 and between the latter and the usual combustion chamber 3 into which the coal or other fuel may be fed after 15 detaching a removable door 4 which closes an opening in the top portion of the stove. The body part of the stove, or the portion which laterally houses the combustion chamber 3, has adjacent to its top an inwardly directed ledge 5 which serves for supporting the top portion of the stove and also for supporting a movable member which operates both for forming wall portions of a flue chamber and for catching drip from the flue 20 pipe. This member, which is more fully described as to its purposes in my U. S. Patent No. 1,515,249 of November 11, 1924 on a slow burning stove, is here shown as comprising a riser wall 6 extending substantially 25 from one side wall of the stove to the other and up to the bottom of the flue collar 7, together with a bottom plate 8 which is recessed opposite each side of the stove as shown in Fig. 4 so as to afford passages 9 of restricted size leading from the 30 combustion chamber 3 of the stove towards the flue 10. This removable member desirably also has a handle 11 on the side of the riser directed towards the door 4, by 35 means of which the said member can be grasped and withdrawn through the opening which is normally closed by this door, so as to remove the flue drip and the like which collects on the bottom plate 8 when 40 the stove is employed with poor grades of coal.

In the stove as thus pictured, the said ledge 5 serves also for supporting a top casting 12 which has an integral curved riser 45 forming the rear half of the flue collar 7. The companion portion of this flue collar is here shown as formed by the upper end of a casting 14 bolted to the back of the stove, this casting being of a substantially U-shaped section and extending down alongside the stove past the combustion chamber 3 and past a rear outlet opening 15 in the ash-pit 2. When thus arranged, as shown in Figs. 1 and 2, this casting cooperates with 50 the adjacent stove walls in affording a by-pass duct 16 through which air can readily pass from the ash-pit of the stove to the flue chamber 10 (which chamber effectively forms the lower part of the flue) without 55 first passing through the bed of fuel on the

grate. Rockingly mounted within this by-pass duct 16 is a damper 17 fastened to a shaft carrying a lever arm 18 which in turn is connected through a link 19 to a lever 20 resting upon the top of an expansible thermostatic member 21. The lever 20 and the thermostatic member 21 are here shown as carried by a bracket 22 fastened to the back of the stove, and it will be obvious from Fig. 1 that when the thermostat 21 (here shown as double-decked to amplify its power) is expanded by a rise in temperature, the said connections to the shaft of the damper will rock the latter so as to open the by-pass duct 16. 70

This by-pass duct has a portion of the rear wall 23 as its own forward wall, the duct being continuously heated by direct radiation from the combustion chamber of the stove, so that the air in the duct is normally warm and will readily rise as soon as the opening of the damper permits its free movement. Consequently, as soon as this damper is opened even to a relatively small extent, a decided upward current of air 90 ensues through this duct and up the flue. Since the by-pass duct as thus arranged affords a direct connection between the ash-pit and the flue, the air entering the ash-pit through the usual draft openings of the stove will flow through this duct instead of passing through the bed of fuel which offers a relatively much higher resistance to the passage of such air. Consequently, the upward movement of air through the by-pass is quite rapid as soon as the damper is opened at all, and since the movement of the check draft air is effected by the heating of air within the said duct, this movement does not depend upon the normal flue draft of the stove. I can therefore obtain a speedy draft control even with low barometric conditions and even when the stove is filled with fuel to such an extent as to cause the fuel to burn at a quite slow rate. 100 Then, as soon as the air in the vicinity of the stove has cooled sufficiently to affect the thermostat 21, the weight of the lever 20 and link 19 will automatically close the damper 110 again. 115

By employing a by-pass duct 16 of relatively large cross-section, I can normally entrap a sufficient quantity of air in this duct to insure a strong movement of the check draft air as soon as the damper is even partially opened and hence can secure a highly responsive control with my stove. Furthermore, it will be evident from Figs. 1 and 4 that my arrangement readily lends itself to the employment of a drip catching member such as that shown in the upper portion of the stove of Fig. 1, thereby permitting the collecting and the occasional removing of the tarry mass which results from the cooling of cold distillates in the 125 130

flue pipe and from the downward trickling and dripping of these cooled portions.

However, while I have heretofore illustrated and described my invention in an embodiment employing highly desirable features, I do not wish to be limited to the various features of construction and arrangement thus disclosed, it being obvious that they might be varied in many ways without departing either from the spirit of my invention or from the appended claims. For example, instead of taking all of the check-draft air from the ash-pit through the by-pass duct 16 after the manner shown in Fig. 1, I may also provide an auxiliary draft duct through which check draft air may be taken from outside the stove. Thus, Fig. 6 shows a stove which such an auxiliary check draft duct 24 open at its lower end to the outer air, this duct being controlled by a damper 25 fastened to the same shaft with the damper 17 which controls the by-pass duct 16 and hence controlled in position by the same thermostat and lever arrangement.

I claim as my invention:—

1. The combination with a stove having an ashpit below its combustion chamber, of a flue chamber connected to and overhanging the upper portion of the said combustion chamber, a flue pipe leading from the flue chamber, and an air by-pass duct leading from the ashpit to the flue chamber, the flue chamber having a bottom disposed under the lower end of the flue pipe and having a lateral opening also below the flue pipe and to which the said duct is connected, and means responsive to the temperature outside the stove for controlling the duct.

2. In a stove having an ashpit below its combustion chamber and having a flue connected to the upper part of the combustion chamber, a check draft duct extending upwards alongside the combustion chamber and in direct heat conducting relation to the latter and leading to the flue, the said duct being open to the outer air at its lower end.

3. In a stove having an ashpit below its combustion chamber and having a flue connected to the upper part of the combustion

chamber, a pair of check draft ducts extending upwards alongside the combustion chamber and in direct heat conducting relation to the latter, one of the said ducts being open to the outer air at its lower end and the other being connected at its lower end to the ashpit, both ducts being connected at their upper end to the flue.

4. In a stove having an ashpit below its combustion chamber and having a flue connected to the upper part of the combustion chamber, a pair of check draft ducts extending upwards alongside the combustion chamber and in direct heat conducting relation to the latter, one of the said ducts being open to the outer air at its lower end and the other being connected at its lower end to the ashpit, both ducts being connected at their upper end to the flue, and dampers respectively disposed in the said ducts.

5. In a stove having an ashpit below its combustion chamber and having a flue connected to the upper part of the combustion chamber, a pair of check draft ducts extending upwards alongside the combustion chamber and in direct heat conducting relation to the latter, one of the said ducts being open to the outer air at its lower end and the other being connected at its lower end to the ashpit, both ducts being connected at their upper end to the flue, and operatively connected dampers respectively disposed in said ducts.

6. In a stove having an ashpit below its combustion chamber and having a flue connected to the upper part of the combustion chamber, a pair of check draft ducts extending upwards alongside the combustion chamber, one of the said ducts leading from the ashpit to the flue and having a wall portion in common with the combustion chamber, the other leading from the outer air to the flue, and operatively connected dampers respectively controlling the two ducts, the said other duct being smaller in cross-section than the duct leading from the ashpit to the flue.

Signed at Macomb, Illinois, April 30, 1924.

HUGH L. GADDIS.
